UNITED STATES PATENT OFFICE.

CHARLES D. COLLINS, OF NEW YORK, N. Y., ASSIGNOR TO AMERICAN CYANAMID COMPANY, OF NEW YORK, N. Y., A CORPORATION OF MAINE.

CLOSURE.

Application filed January 23, 1925. Serial No. 4,171.

This invention relates to closures, more particularly to a structure for use on shipping containers for highly volatile liquids.

Of recent years the use of liquid hydrocyanic acid for the fumigation of citrus trees, factories, warehouses, ships and the like for the eradication of insects, vermin and rodents, has assumed considerable importance. The fumigant is produced at a convenient place, is liquefied, filled into steel cylinders of a type generally used for liquefied gases, and is thus shipped to the point of use. Since hydrocyanic acid is an extremely poisonous material great care must be taken in transferring it from the cylinder to containers for immediate use to prevent the escape of even small quantities thereof into the air. To accomplish this the closure is provided with a valve controlled outlet for the liquid and an air inlet controlled by a spring-pressed valve, whereby air pressure may be placed on the liquid which is thus forced through the outlet into a suitable container, such as the tank of a portable fumigating apparatus or direct to the fumigating lines. Such a closure structure is described and claimed in the co-pending application of Kenneth F. Cooper, filed Feb. 17, 1923, Serial No. 619,746, for closures for shipping containers, and assigned to the American Cyanamid Company.

Being acid in character the fumigant has a corrosive action on the material of the cylinder, and especially of the closure therefor. As a result, if a considerable length of time elapses between the date of shipment and the date of use of a cylinder, as is often the case, the corrosion may be great enough to cause the valves in the closure to stick. This not only renders it difficult to open the cylinder and to force air thereinto to expel the fumigant but it also introduces an element of grave danger to the operator by reason of a sudden release of the valves due to manipulation and a consequent sudden release of a portion of the toxic fumigant into the air.

My invention is intended to obviate these difficulties, it being among the objects thereof to provide a closure structure which shall prevent the accidental release of fumigant into the air, and in which various parts may be readily removed for replacement.

In practicing my invention, I provide a closure of the type described in the aforesaid

application of Cooper, having a fumigant or gas exit opening or outlet closed by a valve which is threaded into the body of the closure and is adapted to seat and thus cut off the opening. Because of the construction of the valve spindle, in unscrewing the same to allow the flow of fumigant, it has sometimes been completely disengaged from the threads allowing the fumigant to flow out into the air. To prevent this I provide a shoulder on the spindle which is adapted to make contact with a stop member on the body of the closure and thus prevent complete removal thereof upon unscrewing.

The air valve structure being composed of delicate parts, including a brass spring and rubber valve seats, which were in contact with the fumigant, became corroded readily. To obviate this I insert a cut-off valve of rugged design in the passage between the air valve and the fumigant, so that when the cylinder is not in use, there is no contact of fumigant with the air valve. I, furthermore, so construct the air valve itself that if the parts thereof become damaged or corroded, it may be readily removed and replaced without any hazard to the operator.

In the accompanying drawings constituting a part hereof and in which like reference characters indicate like parts:

Fig. 1 is a plan view of my closure construction;

Fig. 2 is a vertical, cross-sectional view thereof taken along the line II-II of Fig. 1, and

Fig. 3 is a vertical cross-sectional view taken along the line III-III of Fig. 1.

I provide a block or body member 1, the lower portion 2 of which is threaded and is adapted to fit into the cylinder, not shown, containing a volatile liquid or a liquefied gas. The upper portion thereof is provided with angular portions 3 for the reception of a suitable tool for threading block 1 into the cylinder. A threaded opening 4 in the lower end thereof is adapted to hold a pipe, not shown, which extends to or near the bottom of the cylinder. The said opening connects with opening 5 by means of passage 6, the open end of which is permanently closed by a plug 7.

A seat 9 is formed at the junction of opening 4 and passage 6 and a valve 10, having a threaded portion 11 cooperating with a correspondingly threaded portion of an

opening extending to the upper end of the block 1, is adapted to fit upon the said seat 9. A stem 12 is formed on the valve, the diameter of the stem being materially less than the diameter of the threaded portion 11 forming a shoulder 13 therebetween. Metal washers 14 between which are placed non-metallic packing rings 15 are held in place around the stem 12 by a packing gland or sleeve 16, threaded into the block 1. The extreme end 17 of the stem is formed with angular portions for the reception of a suitable tool for actuating the valve 10 and the plug 18 provides a tight closure to prevent leakage during shipment and protects the valve stem from injury and dirt. A similar plug 19 is inserted into the threaded end 20 of opening 5 for the same purpose.

An opening 21 in the lower end of the block 1 connects with opening 22 in the upper end thereof by passage 23, the open end of which is permanently closed by plug 24. A valve seat 25 is formed at the junction of opening 21 and passage 23 and a valve 10', of the same construction in all essential respects as valve 10, Fig. 2, is adapted to seat thereon.

A sleeve 26, the upper portion 27 of which is threaded, is screwed into the threaded portion of opening 22 until the lower end 28 of said sleeve is securely seated on the walls of said opening to form a gas-tight seal. An air valve of suitable construction, such as the well-known Schrader valve, is inserted 35 in sleeve 26, the upper end of which is provided with slots 30 to facilitate insertion and removal thereof. A protective plug 31 is threaded into the open end of opening 22.

The operation of the device is as follows: Assume that the block 1 is inserted in a cylinder of liquid hydrocyanic acid and a pipe, threaded into opening 4, extends to the bottom of said cylinder. All the valves are closed and the various plugs are in place. To remove liquid from the cylinder the plugs 18, 19 and 31 are removed and a pipe leading to the container into which the hydrocyanic acid is to be transferred is threaded into opening 20. A connection from a suitable air pump, usually manually operated, is threaded into the upper end of opening 22 in place of plug 31. Valve 10' is then opened and air pressure applied by means of the pump, forcing air through air valve 29, passage 23, opening 21, and over the surface of the liquid in the cylinder causing the same to flow out through opening 4, passage 6 and opening 5 into the container, upon opening the valve 10. When a sufficient amount has been transferred the air pressure is removed, allowing the valve 29 to close by the action of its spring, and valves 10 and 10' are seated on their respective seats 9 and 25. The plugs 18, 19 and 31 are then threaded into place.

A cylinder of hydrocyanic acid standing in the sun or in a hot room will develop a considerable pressure due to vaporization thereof and with the prior structure of valve it sometimes occurred that the valve 10 when 70 being opened was completely unscrewed from the threads and the pressure of the gas forced the same completely out of the block not only causing a loss of valuable material but endangering the lives of those in the 75 vicinity. It will be noted that because of the construction of my improved valve, it is impossible during the manipulation thereof to cause the same to be completely removed from the threads. When the valve is opened 80 by turning, the threaded portion 11 is moved upwardly until the shoulder 13 strikes the lower metal washer 14 which is held firmly in place by the packing gland 16 and acts as a stop, thus making it impossible to remove 85 the same completely, either by further turning of stem 12 or by pressure of gas in the cylinder.

By providing a cut-off valve 10' in the air inlet opening, as shown in Fig. 3, the 90 access of the corrosive fumigant to the air valve is entirely prevented and even if some of the fumigant should come in contact with the air valve and corrode it or if the valve should deteriorate by weathering or from 95 other causes, it is an extremely simple matter to replace the same. To accomplish this a suitable tool is inserted in slots 30 of sleeve 26 and the entire air valve structure unscrewed from its threads. A new valve may 100 then be readily inserted. Because of the cut-off valve 10' it is impossible for the fumigant, even though it may develop a high pressure, to spurt out of the opening 22. By these various changes in design and construction of my new closure, I have succeeded 105 in eliminating all danger to the operator and have made it an extremely simple matter to maintain the closure in working order.

Although I have described my invention 110 setting forth the details of a single embodiment thereof, I am not limited thereto. For instance, I may eliminate the Schrader valve from the block 1 in order to avoid any possibility of corrosion thereof, and rely upon 115 valve 10' and plug 31 to prevent leakage during storage and shipment. In use, the plug 31 is removed and a Schrader valve threaded in its place and connected to a 120 source of air pressure. The operation is identical with the form of closure shown in Figures 2 and 3.

What I claim is:

1. A closure for shipping containers comprising a block having an exit opening and 125 a spring valved air inlet opening, and valves seated in said block adapted to close off said openings.

2. A closure for shipping containers comprising a block having an exit opening and 130

- a spring valve air inlet opening, and valves seated in said block adapted to close off said openings, said valves being contained within the body of said block.
5. 3. A closure for shipping containers comprising a block having an exit opening and a spring valved air inlet opening, valves seated in said block adapted to close off said openings, said valves being contained within the body of said block, and plugs for capping said openings and valves.
4. A closure for shipping containers comprising a block having an exit opening and a spring valved inlet opening, a valve adapted to close off said exit opening including a portion threaded into said block and having a valve body formed at the lower end cooperating with a valve seat in the block, and means within the block for preventing complete removal of said portion.
5. A closure for shipping containers comprising a block having an exit opening and a spring valved air inlet opening, a valve adapted to close off said exit opening including a portion threaded into said block and having a valve body formed at the lower end cooperating with a valve seat in the block and means on said portion and entirely within the block for preventing complete removal of said portion.
6. A closure for shipping containers comprising a block having an exit opening and a spring valved air inlet opening, a valve adapted to close off said exit opening including a portion threaded into said block and having a valve body formed at the lower end co-operating with a valve seat in the block and a shoulder on said portion co-operating with a stop in said block for preventing complete removal of said portion.
7. In a closure for shipping containers having a valved exit opening, an air inlet structure comprising a threaded opening in
- the closure, a sleeve threaded into said opening, and an air valve in said sleeve, whereby 45 the entire air valve structure may be removed for replacement.
8. In a closure for shipping containers having a valved exit opening, an air inlet structure comprising a threaded opening in 50 the closure, a sleeve threaded into said opening, and an air valve in said sleeve, the lower end of said sleeve forming a gas-tight joint with the walls of said threaded opening.
9. A closure for shipping containers comprising a block having an exit opening and an air inlet opening, valves seated in said block adapted to close off said openings, and means for inserting a spring valve in 55 said air inlet opening. 60
10. A closure for shipping containers comprising a block having an exit opening and an air inlet opening, valves seated in said block adapted to close off said openings, plugs for capping said openings and 65 valves and means for inserting a spring valve in said air inlet opening.
11. A closure for shipping containers comprising a block having an exit opening and an air inlet opening, valves seated in 70 said block adapted to close off said openings, plugs for capping said openings and valves and means for inserting a spring valve in said air inlet opening in place of the plug therefor. 75
12. A closure for shipping containers comprising a block having an exit opening and a spring valved air inlet opening, and valves seated in said block adapted to close off said openings, said valves and openings 80 being at the top and bottom only of said block.

In testimony whereof, I have hereunto subscribed my name this 21st day of January, 1925.

CHARLES D. COLLINS.
